H. J. Mahin
INVENTOR.

UNITED STATES PATENT OFFICE.

HAROLD J. MAHIN, OF NEW YORK, N. Y.

DESIGN FOR A BULLETIN-BOARD.

55,627.

Specification for Design.

Patented July 6, 1920.

Application filed December 20, 1919. Serial No. 346,394. Term of patent 7 years.

To all whom it may concern:

Be it known that I, HAROLD J. MAHIN, a citizen of the United States, residing at New York, in the county of New York and State of New York, have invented a new, original, and ornamental Design for Bulletin-Boards, of which the following is a specification, reference being had to the accompanying drawing, forming part thereof.

I claim:

The ornamental design for a bulletin board, as shown.

H. J. MAHIN.
